(57) **CLAIM**

The ornamental design for a lever mount, as shown and described.

DESCRIPTION

FIG. 1 is a front, right side perspective view of one embodiment of a lever mount showing my new design; FIG. 2 is a left end elevational view thereof; FIG. 3 is a right end elevational view thereof; FIG. 4 is a right side elevational view thereof; FIG. 5 is a left side elevational view thereof; FIG. 6 is a top plan view thereof; and, FIG. 7 is a bottom view thereof; and, FIG. 8 is a perspective view thereof, shown in its environmental use. The broken lines therein are for illustrative purposes only and form no part of the claimed design.
